US00D657774S

(12) **United States Design Patent**
Chung et al.

(10) **Patent No.:** **US D657,774 S**
(45) **Date of Patent:** **** Apr. 17, 2012**

(54) **MINI COMPONENT AUDIO**

(75) Inventors: **Yeon-Moo Chung**, Seoul (KR);
Min-Hee Lee, Seoul (KR); **Seok-Won**
Hong, Seoul (KR); **Gyoo-Sang Choi**,
Seoul (KR)

(73) Assignee: **Samsung Electronics Co., Ltd.**, Suwon
(KR)

(**) Term: **14 Years**

(21) Appl. No.: **29/393,936**

(22) Filed: **Jun. 10, 2011**

(30) **Foreign Application Priority Data**

Jan. 27, 2011 (KR) 30-2011-003584

(51) **LOC (9) Cl.** **14-01**

(52) **U.S. Cl.** **D14/168**

(58) **Field of Classification Search** D14/496,
D14/498-511, 167-168, 188, 197-198, 214;

(57) **CLAIM**

The ornamental design for a mini component audio, as shown and described.

DESCRIPTION

FIG. 1 is a top front perspective view of a mini component audio showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
